UNITED STATES PATENT OFFICE.

WALTER I. GREGORY, OF NEW YORK, N. Y.

REAMING-TOOL.

1,199,173.

Specification of Letters Patent. Patented Sept. 26, 1916.

Application filed August 27, 1915. Serial No. 47,718.

To all whom it may concern:

Be it known that I, WALTER I. GREGORY, a citizen of the United States, and a resident of New York, in the county of New York and State of New York, have invented a new and Improved Reaming-Tool, of which the following is a specification.

My invention relates to the class of reamers that are adapted to ream holes of varying size, and an object of my invention, among others, is to provide a reamer of this type that shall be simple in construction and particularly efficient in operation.

One form of reamer embodying my invention and in the construction and use of which the objects herein set out, as well as others, may be attained, is illustrated in the accompanying drawings, in which—

Figure 1 is a side view of my improved reamer, shown as held in a chuck. Fig. 2 is a similar view as seen from a point located at right angles to the point of view of Fig. 1. Fig. 3 is a detail view in cross section on plane denoted by dotted line 3—3 of Fig. 2. Fig. 4 is a detail view showing the members separated, parts being broken away to show construction. Fig. 5 is a view showing a slightly different form of tool embodying the invention. Figs. 6 and 7 are views showing other slightly different forms of devices embodying the invention.

My improved reamer consists of two members 4—5 that are substantially duplicates of the other, the meeting faces 6 extending in a diagonal plane with respect to the axis of the tool so that each piece tapers gradually from one end to the opposite end. Each of the corners of these pieces comprising the tool is formed with a cutting edge 7, as clearly shown in Fig. 3. A tongue 8 extending lengthwise of each of the members is located in a groove 9 in the opposite member as a means for holding the members against lateral displacement one with respect to the other. Slots 10 are formed through each of the members through which screws 11 or like fastening means extend into the opposite member and by means of which the two members are adjustably secured one with respect to the other. Both of the members are thus adapted to be inserted within and held by a chuck 12 and by changing the position of the members lengthwise one of another the size of the hole to be reamed may be varied as desired.

The formation of the interengaging

tongue and groove may be varied. As shown herein the tongue extends for a portion of the distance only along one member and the groove for the remainder of the distance in line with the tongue. By this means the two members are formed duplicates one of the other so that in constructing the device a number of parts are formed any two of which may be assembled to comprise the complete tool. This construction of the tongue and groove, and in fact other parts may be varied to a greater or lesser degree and yet be within the spirit and intent of the invention and scope of the appended claims.

In Fig. 5 there is shown a slightly different form of device embodying the invention in which the inclined faces 13—14 are disposed in different planes, and are inclined to a greater degree than in the device of the other figures, this to adapt the tool to wider variations in use.

In the form of the device shown in Fig. 6 the members 15—16 have inclined meeting faces, as in the other devices, the part 15 in this form of the device having a tongue 17 extending its whole length and fitting a groove 18 in the member 16. The operation of the device is substantially the same as that of the other devices hereinbefore described.

In the form of device shown in Fig. 7 there is a body part 19 having a shank 20 adapted to be secured within any proper holder as a drill spindle or the like, and a detachable member 21 is secured to this body part. An intermeshing tongue and groove 22—23 upon these members retain them against lateral movement, as in the form of the device shown in Fig. 6, and the device is similar to the device of Fig. 6 with the exception that the member 21 is not of the same length as the member 19.

I claim—

1. A reaming tool comprising two members of substantially equal length and having inclined meeting faces, and means for securing the members together in different positions one with respect to the other, said members being provided with cutting edges.

2. A reaming tool comprising two members of substantially equal length and having inclined meeting faces, interengaging parts upon the members to prevent lateral displacement, and means for securing the members together in different positions

lengthwise thereof one with respect to the other, said members having cutting edges.

3. A reaming tool comprising two members of substantially equal length and having inclined meeting faces, a tongue extending lengthwise along one member engaging a groove extending lengthwise along the other member, and means for securing the members in different positions lengthwise 10 each of the other, said members being provided with cutting edges.

4. A reaming tool comprising two members of substantially equal length and having inclined meeting faces, means for preventing lateral displacement of said members one with respect to the other, each member having a slot, and screws extending through said slot in one member into a threaded hole in the opposite member to adjustably secure the members together.

5. A reaming tool comprising two members duplicates each of the other and having inclined meeting faces, and means for securing the members together, said members having cutting edges.

6. A reaming tool comprising two members duplicates each of the other, said members having inclined meeting faces, means for preventing lateral movement of said members one with respect to the other, and means for securing the members together in different positions lengthwise one of the other, said members having cutting edges.

7. A reaming tool comprising two members duplicates each of the other, said members having inclined meeting faces and interengaging tongues and grooves extending lengthwise thereof, and means for securing said members together in different positions

lengthwise one with respect to the other, 40 said members having cutting edges.

8. A reaming tool comprising two members having inclined meeting faces, each member comprising substantially half of the working portion of the tool, and means 45 for securing the members together in different positions one with respect to the other, said members being provided with cutting edges.

9. A reaming tool comprising two members having inclined meeting faces, each member constituting substantially half of the working portion of the tool, intermeshing tongued and grooved parts upon said members, and means for securing the members together in different positions one with respect to the other, said members being provided with cutting edges.

10. A reaming tool comprising two members having inclined meeting faces and each member constituting substantially half of the working portion of the tool and said members together forming a tool rectangular in form in cross section, and means for securing the members together in different 65 positions one with respect to the other, said members being provided with cutting edges at their corners.

11. A reaming tool comprising a plural number of members having inclined meeting faces, and means for securing the members together in different positions one with respect to the other, said members being provided with cutting edges.

WALTER I. GREGORY.
